UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed September 22, 1924. Serial No. 739,020.

This invention relates to improvements in typewriting machines, and more particularly to certain innovations in an Underwood standard typewriter.

The improvement includes the provision of an extra or spare platen built into the machine, both of the platens being equipped with individual controlling mechanism, thus providing two independent work-handling units in one machine. The need for a spare platen may arise, for example, where one work-piece is already set up in the machine and it becomes desirable to insert and type upon another work-piece without removing or disturbing the first. A simple, efficient and inexpensive brace is provided to steady the two platen-cylinders which meet in the center, without the use of journals and the like. This brace forms a central support for the inner ends of the platen-cylinders which, at their outer ends, are suitably supported by collars operatively secured around the platen-shaft. The brace is secured directly to a part of the movable carriage and reinforces the platen-shaft centrally. The provision of the spare platen facilitates the expeditious handling of various other kinds of work, including the typing of bills on one platen while a record or ledger sheet is typed upon the other platen, a rapid inserter being provided with each platen for the attainment of speed in connection with properly positioning a work-sheet with its upper edge spaced the requisite distance above the printing line, as will be readily understood by those skilled in the art.

Another feature of the present invention is the provision of means for predetermining the extent of movement of the rapid inserter by means of visual indications inscribed upon suitable bracket-plates which are secured upon the end supports of the usual carriage-frame for the purpose of positioning, by a single stroke or sweep of an operating handle, the upper edge of the work-sheet with respect to the printing line of the machine.

In carrying out the details of construction certain economies in the operation of the platen are attained which will be hereinafter explained, and various parts responsible for

the rotation of the platen for line-spacing and work-sheet positioning purposes are reorganized in a more compact manner.

In connection with the operation of the split platen, there are provided two finger-knobs, one for rotating one of the platen-cylinders at either side of the machine, and the other for rotating the remaining platen-cylinder.

There is also provided a tearing-off knife with novel means for lowering the same into operative position relatively to the platen, or for raising the same to inoperative position.

Other features and advantages will herein-after appear.

In the accompanying drawings, Figure 1 is a top plan view, partly broken away, of the parts of the present invention.

Figure 2 is a side elevation of parts of the present invention, partly in section.

Figure 3 is a front elevation of a bracket-plate.

Figure 4 is a front elevation of a stop-member provided with a positioning latch.

Figure 5 is a front elevation, partly in section, of certain parts shown in Figure 1.

Figure 6 is a cross-sectional elevation of the invention showing the central brace interposed between the meeting ends of the platen-cylinders.

Figure 7 is a fragmental side elevation of parts shown in Figure 2.

Figure 8 is a front elevation of the bracket-plate, partly broken away, showing the relative positions occupied by the rapid inserter, the stop therefor, and carriage-release lever.

In the drawings, 10 designates the forward ledge of the typewriting machine having a bracket 11 in which is guided a roller 12 of the adjacent portion of the carriage 13 carrying a slotted guide 14 in which is manually shiftable a line-spacing lever 15 which has a hub 16 journaled on a pin 17 suitably mounted upon the carriage-frame. The lever 15 has a pusher 18 arranged to contact with a spacer slide 19 which has a pin 20 connected to a retractable spring 21 which applies tension against the movement of the slide 19.

The slide 19 has a spring 22 which presses a pawl 23 into driving relation against a ratchet-wheel 24 fixed upon a platen-shaft 27 which extends through the end supports 25 of a platen-frame to which are secured the horizontal flanges 26 of bracket-plates 25 which extend in parallel relation to the end supports 25^a to produce, with the latter, housings, the end supports 25^a having openings 28 into which the platen-shaft 27 projects rotatably. A finger-knob 29 is secured at one end of the platen-shaft 27, and another finger-knob 30 is secured to the other end thereof, the latter projecting beyond both end supports 25^a of the platen-frame. The carriage-frame has side walls 86^a extending into the housing formed by the end supports 25^a and the bracket-plates 25, these side walls being disposed in advance of the end supports 25^a, and the ratchet-wheels 24 being disposed in advance of these side walls.

A bushing 31 is fixedly secured upon the platen-shaft 27 between the ends thereof, as shown in Figure 6, and has an integral flange 32 formed thereupon of the same thickness as an annulus 33, the flange 32 snugly projecting in rotatable fashion within the annulus 33, so as to be braced and supported by the latter. The annulus 33 has an arm 34, secured upon a fastening pin 35, fixed upon a lug 36, formed upon an angular support 37, secured upon an out-struck ledge 38, cut out preferably from a paper-shelf or paper-table 39, a set screw 40 removably securing the angular support upon the ledge 38. The annulus 33 is also provided with an arm 41 arranged so as to extend in an opposite direction with respect to the arm 34. A fastening pin 42 positions the arm 41 fixedly upon a lug 43 formed upon a support 44 secured by fasteners 45 upon the cradle or under part of the platen-frame structure 46.

Screws 47 preferably secure the platen-cylinder 48 in contact with the flange 32 of the bushing 31, the diameters of the cylinder 48 and flange 32 being the same. A sheathing 53 envelops the platen-cylinder 48 and makes the outside circumference thereof equal in diameter to the outer circumference of the annulus 33, the side of said annulus engaging the adjacent edge of the sheathing 53. Another platen-cylinder 48^a is arranged adjacent the shaft 27 in longitudinal alignment with the cylinder 48, and also has a rubber sheathing 53 similar to that already described and of the same diameter therewith. The platen-cylinder 48^a has a concentric longitudinally-extending sleeve 49 which fits around the shaft 27, and which contacts with the flange 32. A bushing 50 is fixed upon the inner end of the sleeve 49, and has a flange 51 contacting with the flange 32 of the bush-

ing 31 rotatably, this flange 51 being secured to the platen-cylinder 48^a. The sleeve 49 projects beyond one of the end supports 25^a and is secured, at its extreme outer end, by a fastener 55 to a finger-knob 54 by which the sleeve and the platen-cylinder 48^a may be manually rotated.

The platen-cylinders 48 and 48^a are tubular and the flanges 32 and 51 close the inner ends thereof, while their outer ends are respectively closed by end plates 56 having hubs 57, the hub of one plate being secured to the sleeve 49 by a fastener 58, while the other end-plate 56 has a hub 57 secured by the fastener 58 directly to the platen-shaft 27.

A feed-roll release-handle 59 has a crank 60 fulcrumed upon a pin 61 which is secured upon one of the bracket-plates 25, and the crank 60 has a link 63 connected to it by a pin 62, which link operates a crank 66 secured upon a main shaft 67 arranged in the lower part of the cradle 46. A stop 64 is carried by the crank 60 for limiting the extent of movement of the feed-roll-release lever 59. Cranks 68 are secured upon the shaft 67 at opposite ends thereof, and these cranks are connected to suitable fork-shaped links 69 secured upon a counter-shaft 75, the ends of which are suitably supported by holders 83 secured upon the paper-shelf 39, the forward edge of which forms a paper-guide or clamp 81 extending longitudinally of the platen. The means for clamping the paper-clamp onto the platen, or releasing it therefrom, is the same as described in Patent No. 1,332,263, granted to Alfred G. F. Kurowski, March 2, 1920. A pair of spiders 76 are secured fixedly at the opposite ends of the counter-shaft 75, and operatively mounted in the opposite arms of each spider are longitudinal rods 77 and 78, upon each of which are journaled longitudinally-separated feed-rolls 79 and 80 which project through slots 75^a formed in the paper-clamp, so as to rotatably engage the platen-cylinders 48 and 48^a. Formed upon one side of each spider is a stud 75' which is slidably mounted in a recess or slot 74 of one of two slotted bearings or forks 69^a, so as to have vertical movement therein. Two coil springs 71 are suitably secured to the shaft 67, and through a connection 70, each spring is secured to one of the links 69.

Secured in the side walls 86^a of the main carriage-frame is a pin 85 upon which is fulcrumed a lever 86, which lever is disposed immediately beneath the ratchet-wheel 24. The lever 86 is operatively connected to the rack-bar 92 which meshes with the usual pinion 92^a, this rack-bar 92 being mounted upon the carriage of the machine and serving to urge the carriage along step by step during the depression of the keys.

Secured to lever 86 by fasteners 88 is a lug 87 having a horizontally-extending arm 89, which supports and spaces, laterally of the housing in which the ratchet-wheel 24 is mounted, an operating arm 90 of a handle 91, which handle is the carriage-release handle.

93^a designates a lever which has a part 93^b journaled operatively upon the shaft 27 in back of the bracket-plate 25, and within the adjacent housing, and this lever 93^a is offset at 93^c to position an integral handle 93 outside the housing, the lever 93^a projecting movably into a recess 106 formed in the adjacent bracket-plate 25, as shown in Figures 2 and 3. A finger-piece 94 is mounted upon the handle 93. The lever 93^a is also formed integrally between its ends with a recess or notch 97, and in a plane with this notch is a cam 95 which merges into a hook 96. A lever 98 (Figure 7) is fulcrumed upon a pin 100 secured upon the end support 25^a, and a coil spring 101 is secured at 100^a to the end support 25^a, and is also secured to the lever 98, so as to urge a roller detent or stud 99 fulcrumed at the lower end of the lever 98 into pressed engagement with any of the teeth of the ratchet-wheel 24, this stud 99 holding the ratchet-wheel against retrograde action.

A rapid inserter, actuated by a sweep-lever, is provided which operates independently of the usual line-spacing mechanism, and is designed to carry the platen rotatably around over variable distances, so as to position the upper edge of the work-sheet at variable distances apart with respect to the printing line of the machine, where the first line is to be typed upon the work-sheet.

Each of the bracket-plates 25 has a ratchet-plate 108 secured by removable fasteners 109 to its outer side, which ratchet-plate has a single opening 110 that registers with a recess 110^a formed upon the plate 25. The ratchet-plate has a segmental jagged surface 109^a, and concentrically of the platen there are inscribed upon the outer face of the bracket-plate 25 an arcuate series of marks or calibrations 105 extending radially of the jagged edge 109^a. Opposite each of the marks 105 is one of a consecutive series of numbers 1, 2, 3, 4, etc., as indicated at 104. The marks and numbers form a dial which provides means for predeterminedly actuating the platen-cylinders, separately, over variable distances. A hub or bushing 116 projects partially through the circular opening 110 in the ratchet-plate 108, so as to extend into the adjacent housing, where it is provided with an integral crank 117 adjacent the inner side of the bracket-plate 25. The crank 117 carries a lever 119 yieldably controlled by a spring 122 secured to a pin 135, secured upon the crank 117. Lever 119 carries a wedge-shaped claw or pawl 120

which is urged by the spring 122 into engagement with any of the teeth of the ratchet-wheel 24, as shown in Figure 8.

A band 112 has a collar 112^a secured by a fastener 115 upon the bushing 116, and extending radially of the band 112 is a sweep-lever 113 carrying a handle 114. The band 112 is positioned in advance of the fixed ratchet-plate 108, and rotatably surrounding the band 112 is a ring 126 of a smaller diameter than the fixed ratchet-plate 108. A stop member is mounted so as to move with the ring 126 and consists of a projection 129^a extending radially of the ring 126. The projection 129^a is provided with a pair of angularly-disposed lugs 128' and 129' arranged in stepped relation, and formed right angularly upon lug 128' is a pointer edge 128, while a stop edge 129 is formed upon the lug 129'. The pointer edge 128 and stop edge 129 project in opposite directions so that the pointer edge 128 will register with and indicate any of the calibrated radial marks 105 on the bracket-plate 25, while the stop edge 129 will stop or limit the extent of travel or movement, and determine the length of the stroke allowed the operating handle 113, which is arranged to abut this stop 129, as shown in Figure 8.

A coil spring 124 is secured at 97' to the operating handle 113, and extends around the periphery of the band 112, with its other end secured to a pin 98' secured upon an arm 106^a formed integrally upon the bracket-plate 25. In order to hold this spring 124 in position as the operating handle or lever 113 is making a sweep over the calibrated marks 105 on the bracket-plate 25. Normally the operating lever 113 is held by the spring 124 in engagement with a fixed stop 111 which is formed right angularly and integrally upon the bracket-plate 25, at which point this lever is out of range of the dial consisting of the calibrated marks 105.

The projection 129^a is formed with a slot 130 in which is slidably mounted a detent or dog 131, which detent or dog is held in contact and in engagement with the teeth of the fixed ratchet-plate 108 by a spring 134 secured upon a pin 125 and also to a slide 132 connected to the detent, this slide having a handle 133 by means of which the detent can be disengaged from the ratchet-plate against the tension of the spring 134. The detent may then be carried around the ratchet-plate opposite any predetermined tooth thereof, and then the slide 132 and dog 131 are automatically impelled so that the detent may engage with this tooth. When the pointer edge 128 stops opposite any of the calibrated marks 105 it serves to position the detent 131 against one of the teeth of the

ratchet-plate 108, and also to locate the stop 129 in correct position to limit the sweep of the operating handle or lever 113.

102 designates the usual type-bars, and 103 the type-surfaces. When the operating handle 113 engages the stop 111, as shown in Figure 2, the crank 117 is positioned approximately at the lower dead center of the shaft 27, and just before reaching this position, during the return of the handle 113 by the spring 124, the wedge-shaped click or claw 120 engages a fixed pin 121, with the result that the lever 119 and claw 120 are retracted automatically, the claw being disengaged from the ratchet-wheel 24, against the tension of the spring 122, so that unless and until the operating handle 113 is manually operated the ratchet-wheel 24 may be freely line-spaced independently of the action of the rapid inserter controlled by the operating handle 113.

15^a designates another line-space handle at the right hand of the typewriting machine for line-spacing the platen-cylinder 48^a in a manner already explained in connection with the line-spacing of the platen-cylinder 48. The rapid inserter, the dial and the other parts are provided at this side of the machine also. The only difference is that the carriage-release lever 136, at this side of the machine, is located with its operating lever 136^a located within the adjacent end support and bracket-plate.

20 Means are provided for locating a tearing-off knife-bar 142 in operative or inoperative position. Brackets 137 are secured upon the flanges 26 of the bracket-plates 25, and carry standards 138 in which are fixed pins 139 on which are fulcrumed, at opposite sides of the machine, levers 140 formed integrally with forwardly-extending and angularly-disposed arms 141 which terminate in hooks 149 to which the knife-bar 142 is attached, and between which it extends longitudinally with its tearing-off edge engageable with the platen-cylinders 48 and 48^a, as shown in Figure 7. In order to yieldably latch the tearing-off knife in operative down, or inoperative up, position, plungers 145 are provided which are pivotally secured at their inner ends upon pivots 144 secured upon the standards 138, which plungers project telescopically into tubular links 146 pivotally connected by lugs 147 to the levers 140 adjacent the arms 141, coil springs 148 being incased in each tubular link 146 to tension the telescopic action of the plungers 145 in the tubular links 146 as the levers 140 move to horizontal or vertical position, shown in Figure 8. The co-operating plungers 145 and tubular links 146 with the springs 148 provide a latching means, and act as braces for properly positioning the knife-bar 142 in operative position against the platen-cyl-

inders 48 and 48^a. One of the levers 140 engages the fixed stop 138^a on one of the standards 138. When the knife-bar 142 is arranged in inoperative position it may be swung down to occupy a horizontal operative position shown in Figure 8.

The present invention finds application in any class of work wherein it is desired to utilize the advantages of two independently operable platen units, one of the platens being either used as a spare platen or to cooperate with the other platen in handling correlated work-pieces. In the bookkeeping field for instance it is customary to type entries upon bills, and to keep a record thereof, in a ledger account, the sheet A may represent a bill inserted upon the paper-shelf 39 in contact with the platen-cylinder 48, while the sheet B may represent a ledger-sheet similarly positioned against the platen-cylinder 48^a, shown in Figures 1 and 5, these sheets being, of course, held fast onto the platen by the engagement of the feed-rolls 79 and 80, as well as the paper-clamp 81. Ordinarily it may be necessary to progressively type upon each bill certain items of account which are added together, and the total thus obtained is typed upon the bill at which time the same total is to be typed upon the ledger-sheet. Each item of account typed upon the bill thus calls for an intervening line-spacing of the platen, which line-spacings multiply before the total of these items is ready to be typed upon the ledger-sheet; therefore the rapid inserter is provided which will, at one stroke of the proper operating handle 113, carry the platen-cylinder 48^a over a distance equal to the combined line-spacings of the aforementioned bill; or the rapid inserter may turn either 105 platen-cylinder over a predetermined distance to space the upper edge of either the bill or ledger the proper distance from the printing line at one stroke of the operating handle 113.

110 The operator takes hold of the handle 133 to retract the detent or dog 131 from the fixed ratchet-plate 108, which detent is then carried around until the pointer edge 128 registers with any of the calibrated marks 115 105 having that number designated interchangeably 104, which corresponds to the number of line-spacings which are to be combined in one sweep of the operating handle 113. By releasing the detent, the latter 120 clicks into engagement with one of the teeth of the ratchet-plate 108 opposite the predetermined mark 105. The operating handle 113 is then swung away from the stop 111 until it contacts with the stop 129. As it 125 swings the pawl or click 120 engages the ratchet-wheel 24 and carries it around the same distance the operating handle 113 is moved. The operating arm 90 is depressed by the handle 91 to tilt the lever 86 and to 130

disengage the rack-bar 92 from the pinion 92 in a conventional manner.

In order to disconnect or disengage the roller 99 from contact with the ratchet-wheel 24, the finger-piece 94 will be operated. It will be noticed that normally, when the roller 99 engages the ratchet-wheel teeth, it lies in the notch 97 of the lever 98, as shown clearly in Figure 7. When the finger-piece 94 is raised so are the hook 96 and cam 95, and the cam begins to engage the roller and forces it out of contact with the ratchet-wheel 24 until the roller is received and held in the notch of the hook 96 where it is spaced out of contact with the ratchet-wheel. The movement of the roller away from the ratchet-wheel takes place concomitantly with lever 98 and against the tension of the spring 101.

When the feed-roll-release handle 59 is depressed the cranks 66 and 68 are operated so as to move downwardly, whereby the forked links 69 move downwardly against the tension of the coil springs 71, which action draws down the spiders 76, and with them the rods 77 and 78, carrying the feed-rolls 79 and 80. Since the spiders are mounted upon the counter-shaft 75, the latter moves downwardly with the spiders, and through the holders 83, the paper-clamp also moves downwardly. During the downward motion of the spiders the studs 75' thereof slide respectively in one fork 69^a of each of the twin-fork bearings C arranged at each end of the cradle 46, while the spiders themselves slide between both forks 69^a of each bearing, the springs 71 being tensioned during the retraction of the feed-rolls and paper-clamp.

The platen-cylinder 48 may be rotated manually by either the finger-knob 29 or 30 from either side of the machine. The central portion of the platen-shaft 27 is reinforced and supported by means of the flange 32 which rotates upon the inner circumference of the fixed annulus 33, so that the shaft, being suitably supported at this point, serves to properly support thereadjacent the inner end of the platen-cylinder 48^a. The platen-cylinder 48^a, through the sleeve 49, rotates freely about the shaft 27 without imparting any motion to the shaft 27 or the platen-cylinder 48 thereon. The finger-knob 54 is preferably of larger diameter than the finger-knobs 29 or 30, so as to distinguish one platen-cylinder from the other for rotating purposes.

Variations may be resorted to within the scope of the invention, and portions of the improvements may be used without others.

Having thus described my invention, I claim:

In a typewriting machine, the combination of a platen, a platen frame formed with ends, a platen shaft, said platen having

separate independently rotatable sections, a separate ratchet-wheel upon each platen section, fixed ratchets mounted upon said ends and having equally-sized teeth with said platen ratchet-wheels, a fixed stop on each end, movable stops adjustably engaging any of the teeth on said fixed ratchets, and means playing between the fixed and adjustable stops adjacent the ends for turning said platen ratchet-wheels. 75

2. In a typewriting machine, the combination of a downwardly-extending end plate, a platen rotatably journaled therein, a sweep-handle concentrically positioned with respect to said platen in front of said plate for rotating movement, a fixed ratchet-plate secured upon said end plate, an arm rotatable concentrically of said fixed ratchet-plate, a spring-pressed detent retractably mounted upon said arm so as to engage any of the teeth of said fixed ratchet-plate, means controlled by said sweep-handle for rotating said platen, a pair of lugs formed upon said arm, one of said lugs acting as a stop to arrest predeterminedly the movement of said handle, said end plate being inscribed radially of several teeth of said ratchet-plate with calibrated lines, the other of said lugs serving as a pointer and being positionable upon any of said lines to cause said detent to engage one of said teeth of said ratchet-plate, and a spring for restoring said sweep-handle automatically to normal position. 95

3. A device of the kind described consisting of a bushing having a radially-extending arm, said arm being provided with stepped lugs, an angular terminal formed integrally upon each of said stepped lugs, said terminals projecting in opposite directions, a spring-pressed detent slidably mounted in said arm and disposed radially of said bushing, and a handle operating said detent to retract the same manually. 100

4. In a typewriting machine, the combination of a supporting plate, a shaft journaled therein, a platen fixed upon said shaft, a ratchet-wheel fixed upon said shaft, a ratchet-plate secured upon the supporting plate concentrically with said ratchet-wheel, a bushing on said shaft, a collar loosely mounted on said bushing, a sweep-handle on said collar, a crank connected to said collar, a pawl movable around said ratchet-wheel and yieldably mounted upon said crank, a pin projecting from said plate, a spring yieldably holding said pawl, a click secured upon said pawl for engaging said ratchet-wheel, a retractable spring secured at one end to said sweep-handle and at the other end upon said plate and positioning said handle so that said click engages said pin so as to be retracted from engagement with the ratchet-wheel, and manually-operable means adjustably engaging any of the teeth of said ratchet-plate for limiting the move- 120

130

ment of said sweep-handle, said click being urged by said crank to carry said ratchet-wheel around with it during its movement.

5. In a typewriting machine, the combination of a supporting plate having a lateral recess and an integral arm formed thereby, a platen-shaft projecting through said plate, a hub on said shaft mounted in said recess, a platen connected for joint rotation with said shaft, a collar revolvably mounted upon said hub, means arranged to operate said collar, a ratchet-plate fixedly secured to the other plate concentrically of said collar, a stop adjustably engageable with any of the teeth of said ratchet-plate and serving to limit the movement of said means in one direction, a ratchet-wheel for operating said platen, a crank on said collar, a feed-pawl yieldably mounted upon said crank and having a terminal wedge-shaped click engageable with said ratchet-wheel to drive the same around, a pin, a coiled spring secured at one end to said pin having an arcuate bearing around said collar and being secured to said machine, another pin engageable by said wedge-shaped click upon its return stroke, whereby said click is retracted from said ratchet-wheel, and a handle for operating said adjustable stop.

10. In a typewriting machine, the combination of a frame having depending end plates, each of said end plates having a lateral recess, a fixed ratchet-plate, having an annular opening therein, secured upon the outer face of each of said end plates, a hub rotatable in each of said openings, a platen-shaft fixed to said hubs, a platen fixed upon said shaft, a supporting arm movable radially of said ratchet-plate, a spring-pressed detent releasably engageable with the teeth of said ratchet-plate and slidably retractable therefrom, means for rotating said platen, a handle for actuating said means and being pivoted around one of said hubs, means in back of said plate and engageable with said detent to retract the same from said ratchet-plate, and an operating handle for the last-named means offset laterally so as to have a portion located in front of said plate, and so that said operating handle may move freely in said recess.

15. In a typewriting machine, the combination of a rotatable platen, end plates upon which said platen is journaled, a ratchet-wheel for turning said platen, line-spacing mechanism having provision for operating said ratchet-wheel, one of said end plates being provided with a dial, a stop-member pivoted upon said end plate, means carried by said stop-member for latching it at predetermined points of said dial, an indicating edge carried by said stop-member for locating any point of said dial where said stop-member is to be latched, means hold-

ing said stop-member unlatched, a feed-pawl operable independently of the line-spacing mechanism normally retracted from said ratchet-wheel, means for automatically engaging said feed-pawl with said ratchet-wheel to drive the latter, and means having a variable throw controlled by said stop-member for actuating said pawl-engaging means.

20. In a device of the kind described, the combination of a platen, means for rotatably supporting said platen, a ratchet-wheel on said platen, a feed-pawl engaging said ratchet-wheel to drive it, a line-spacing slide for actuating said feed-pawl, an extra feed-pawl also engaging with said ratchet-wheel to actuate it, means concentric with said platen for supporting the last-named feed-pawl, a fixed stop, an operating handle for actuating said second-named means, means for predetermining the distance of movement of said handle away from said stop, a spring engaging said handle to move the same to a position of rest against said stop, and means engaged by the extra feed-pawl just prior to the engagement of said handle with said stop for retracting said pawl from said ratchet-wheel.

25. A device of the kind described consisting of a bracket-plate formed with a medial recess, a downwardly and angularly disposed arm formed integrally upon said plate and intersecting the longitudinal axis of said recess, and a plate removably secured upon said bracket-plate and having a central opening registering with said recess, said plate having a segmental jagged edge, said bracket-plate being inscribed with an accurate series of consecutively enumerated and calibrated marks arranged radially of 30 said segmental jagged edge.

35. In a typewriting machine, the combination of a bracket-plate, a platen-shaft projecting therethrough, a ratchet-wheel on said shaft in back of said plate, a fixed ratchet-plate secured to the outer face of said bracket-plate, an operating handle having a bushing of smaller diameter than said ratchet-plate and disposed in advance thereof, said bushing arranged to rotate upon said shaft, a driving pawl engageable with said ratchet-wheel and carried by said operating handle, a stop-member for limiting the movement of said operating handle, a latch carried by said stop-member engaging the teeth of said fixed ratchet-plate to predetermine the position of said stop-member, a coil spring extending around and over said bushing, and being secured at one point to said plate and also to said operating handle, and a side flange mounted upon said bushing and retaining said spring against lateral displacement from said bushing as said operating handle moves radially of said shaft.

11. In a typewriting machine, the combination of a platen-frame including an end support and a bracket-plate secured upon said end support and forming with the latter a housing, a platen-shaft projecting through said end support and bracket-plate, a platen rotatably mounted upon said shaft adjacent said end support, a carriage upon which said platen-frame is mounted having 10 a side wall extending into said housing, a ratchet-wheel mounted upon said shaft in advance of said side wall, a ratchet-plate secured upon the outer face of said bracket-plate having an opening, a bushing rotatably projecting through said opening into said housing, a crank fixed upon said bushing in said housing, a click yieldably carried by said crank and engaging said ratchet-wheel, an operating handle secured to said bushing in advance of said ratchet-plate, and a 20 stop-member having a latch moving circumferentially of said ratchet-plate and engaging the latter to define stop positions for said operating handle.
